ANNEALING APPARATUS

John R. Wirt and William A. Fletcher, Anderson,
Ind., assignors to General Motors Corporation,
Detroit, Mich., a corporation of Delaware

Application May 22, 1941, Serial No. 394,684

2 Claims. (CL. 219—11)

This invention relates to apparatus for annealing continuously moving lengths of rods, tubing, wire and the like. More particularly the invention relates to an apparatus for annealing welded steel tubing made in a continuous mill comprising forming rolls, a seam welder, an annealer and other apparatus for surface finishing of the tube.

An object of the present invention is to provide an improved annealing apparatus which provides for heating the tube electrically while in an annealing chamber containing an inert or reducing atmosphere. More particularly it is an object of the invention to provide for making good electrical contact with different portions of the tubing by means which distributes the pressure along a substantial portion of the tube, so that the pressure applied to the tubing at any particular point is not so great as to cause it to be distorted while in a relatively soft condition. This is accomplished by the use of the electrode boxes forming parts of the annealing chamber and containing quantities of metal pellets mixed with graphite powder.

In this connection it is a further object to provide for rotatably supported the boxes on an axis coinciding with the axis of the moving tubing so that the boxes may be inverted and the metal pellets and graphite may gravitate to other parts of the boxes and thus clear the space through which the tubing passes so that the tubing may be threaded through the annealing apparatus without interference by the metal pellets and graphite.

Further objects and advantages of the present invention will be apparent from the following description, reference being had to the accompanying drawings wherein a preferred embodiment of the present invention is clearly shown.

In the drawings:

Figs. 1 and 2 taken together comprise a front elevation of a welding apparatus involving the present invention;

Fig. 3 is an end view taken in the direction of the arrow 3 of Fig. 1.

Figs. 4 and 5 are sectional views taken respectively on the lines 4—4 and 5—5 of Fig. 1.

Fig. 6 is a fragmentary longitudinal sectional view of a portion of the annealer at the end of Fig. 2; and

Fig. 7 is a sectional view on the line 7—7 of Fig. 6.

The annealing apparatus comprises a channel iron bed 28 supported by pedestals 21 and 22. 55

At each end thereof, the bed 28 supports brackets 23 and 24 provided with trunnion rollers 25 for supporting tubular shafts 26 and 27 which are fixed between clamp 28 attached by screws 29 to brackets 30 welded to a channel frame 31. Frame 31 supports seven electrode boxes 32 made of cast bronze arranged as shown in Figs. 1 and 2. There are groups of two boxes each located near each end of the frame 31 and a group of three boxes midway between the end groups. The end groups are electrically connected together by bus bars 33 attached by screws 34 to the bottoms of the end boxes 32 and spaced therefrom and from each other by copper plates 35. The bars 33 are insulatingly supported by the middle group of boxes 32. The boxes 32 of the center group are insulated from the boxes 32 of the end groups. Non-conducting plates 36 are located between each of the center groups of boxes and the bus bars 33. The screws 37 which secure bars 33 and plates 36 to the boxes 32 are insulated from the bars 33. The end groups of boxes 32 are grounded upon the frame 31 which is electrically connected with the pedestals 21 and 22. Between the frame 31 and each of the boxes 32 of the end group, there is located a metal spacing block 38 (Fig. 4). Screw 39 secures the end boxes 32 and the middle plate 38 to the frame 31. The boxes 32 of the center group are insulated from the frame 31 by nonconducting spacers 40 (Fig. 5). Screws 41 which secure the boxes of the center group and the insulating plates 40 to the frame 31 are insulated from the frame 31. The center group 35 of boxes 32 are connected together by bus bar 42 provided with a plurality of wire connecting terminals 43 all connected with one pole of an alternating current source, the other pole being connected in a similar manner to the bus bars 33. When the end boxes are charged positively the center boxes will be charged negatively and vice versa during the A. C. cycle. Therefore, current flows either from the end boxes toward the center or in the reverse manner. Since the end boxes are grounded, there is no external circulating current.

Referring to Fig. 6, the right end box 32 provides a back wall 50 integral with top wall 51, bottom wall 52 and side walls 53. The front opening is partly enclosed by cover plate 54 attached by screws 55 (Figs. 1 and 2) which extends a little over half way down from the top wall 51 (Fig. 4). The remainder of the front opening is closed by a removable plate 56 and a fixed bar 57 carrying pairs of spaced ears 58.

each pair supporting a pin 59 pivotally supporting a clamping lever 60. Referring to Fig. 4, each lever 60 is secured in clamping position by engaging the eccentric portion 61 of the lever 62 pivoted at 63 on an arm 64 pivoted at 65 on a bracket 66 attached by screws 67 to the fixed plate 54. By moving the lever 62 down or clockwise in Fig. 4 the lever 60 is firmly wedged into position and holds the plate 56 in position upon the box 32. When the lever 62 is moved upwardly or counterclockwise and the arm 64 is likewise moved upwardly the lever 60 is released so that the plate 56 may be removed.

The plate 56 is attached at each end by screws 70 to blocks 71. Each block 71 is wider than the thickness of the side walls 53 and is provided with grooves 71a each of which receives an end portion 53a of the side wall 53. Block 71 is provided with a semi-circular notch 72 matching with a semi-circular notch 73 provided in side wall 53 and surrounded by semi-annular bosses 74. The distance between flat surfaces of the two bosses 74 on the inside and outside of the box wall 53 is equal to the thickness of the block 71. The wall 53 and the block 71 are shaped to receive a tube of heat resisting and electrically nonconducting material 75. It has been found that a tube of Alsimag is satisfactory for this purpose. The Alsimag tubes are purchased in short lengths so that any section of the tube may be replaced without necessitating replacing the whole line of Alsimag tubing. Between adjacent boxes 32 of each group, one length of tubing 75 is sufficient; and the tube sections between the adjacent boxes are enclosed in a metal protecting band 76. The tubing T to be treated (Fig. 6) moves from right toward left. Therefore, the entrance end of each refractory section 75 is beveled as indicated at 78a. A short refractory section 75' connects each end box 32 with a shaft 26 or 27, the shaft being counterbored for this purpose. The entering end of the shaft 27 is beveled at 27a also to facilitate threading of the tubing through the annealing apparatus.

Each end group of boxes is connected with the other end group of boxes by a line of refractory tubing sections 75" providing a refractory pipe connecting the nearest adjacent boxes of an end group and another group. These refractory sections 75" are enclosed in a tubular case comprising a tubular half shell 80 of steel and tubular half shell 81 of copper or other non-magnetic material (Fig. 5). These two half shells extend nearly the full distance between the nearest adjacent boxes of the center and end groups; but they do not contact any of the boxes so that no electrical connection is made between them. These half shell members 80 and 81 are clamped between pairs of clamping bars 82 and 83. Bar 82 is secured to frame 31. Bar 83 is provided with spaced ears 84 pivoted at 85 upon bar 82. Bar 82 carries a pin 85 providing a pivot for a pair of spaced arms 87 carrying a pin 88 providing a pivot for a lever 89 having an eccentric 90 adapted to clampingly engage the lower end of each bar 83. By pushing the handle 89 down the bar 83 is caused to grip the half shell 81 and to force it against the half shell 80 and thereby secure the two half shells firmly in position. When the handle 89 is raised the eccentric is moved away from the bar 83 a distance sufficient to permit the arm 87 to drop below the end of the bar 83 so that the bar 83 may be swung upwardly about its pivot 85 thereby releasing the half shell

member 81 so that it can be removed to provide access to the refractory lining units 75".

The metallic case comprising the metallic half shell members 80 and 81 encloses the refractory lining unit 75", is inductively related to the tubing T which conducts alternating current. In order to reduce the electrical and magnetic effects upon the members 80 and 81 caused by the alternating current passing through the tubing T, the members 80 and 81 provide electrical gaps at their abutting edges which minimize eddy currents induced in these members. The fact that one of these members is non-magnetizable helps to minimize magnetic effect. The reason that the section 80 is made of steel rather than copper is to increase the resistance to the flow of eddy currents.

Each box 32 houses a quantity of metal pellets 100, preferably of copper mixed with powdered graphite. Practically all of the length of tubing 10 between the side walls 53 of each box 32 is under the pressure of the copper pellets 100. This distributed pressure is sufficient to transfer electric current between the pellets and tubing without requiring the pressure at any point to be so great as to distort the tubing T although it should be heated to such high temperature that its walls would be relatively soft.

While the tubing is passing through the annealing chamber comprising the shafts 26 and 27, the refractory units 75, 75' and 75" and electrode boxes 32, air is excluded by forcing an inert or reducing gas into the boxes and under sufficient pressure to keep the air from entering the annealing chamber. Each box is connected by a coupling 105 of electrically non-conducting material and a flexible pipe 106 with a gas manifold.

In order to facilitate threading the tubing T through the apparatus before the electric current is turned on, the frame 31 and all parts supported thereby are inverted in order that the metal pellets and the graphite may descend upon the walls 51 of the boxes 32. This is accomplished by turning handwheel 110 connected with a shaft 111 journalled in a bracket 112 attached by screws 113 to the trunnion frame 114. Shaft 111 is provided with a worm meshing with a worm wheel 115 welded to a shaft 27. By rotating the shaft 27 at the right end (Figs. 2 and 6) the frame 31 and parts supported thereby and the shaft 26 at the left end (Fig. 1) are rotated about the axis of the tubing T so that conducting pellets 100 and the graphite with which they are coated fall upon the normally upper walls 51 of the boxes 32. The graphite reduces abrasion of tubing by the pellets 100 and assists in making good electrical contact with the minimum sparking.

While the embodiment of the present invention as herein disclosed, constitutes a preferred form, it is to be understood that other forms might be adopted, all coming within the scope of the claims which follow.

What is claimed is as follows:

1. Apparatus for annealing tubing comprising an elongated frame, a plurality of spaced metallic electrode boxes having their back walls attached to the frame and having their side walls provided with openings located closer to their bottom walls than to their top walls, the bottom wall being the lowermost wall in the normal position of the box, the front walls of the boxes being provided with openings to provide access to the openings of the sides to facilitate threading the tubing through the side openings, covers for the

openings detachably secured to the boxes, tubular sections having tubular, refractory, electrically nonconducting lining bodies connected with the boxes at their side openings so as to provide aligned guides for the passage of a length of tubing to be annealed and for the passage of a non-oxidizing gas around the tubing, quantities of electrically conducting pellets located in the boxes for making electrical connections between the boxes and the tubing, the aggregate volume of each quantity of pellets being such that the pellets submerge the tubing to a substantial depth when the boxes are in normal position, the size of the pellets being in excess of the clearance between the tubing and the refractory bodies, means for supporting the frame for rotation about the axis of the tubular sections, means for rotating the frame in order to cause the pellets to slide down the back walls of the boxes into pockets provided by the front, back, side and top walls of the boxes, the pockets being of such dimensions as to receive the pellets so that they are below the side-openings of the boxes, thereby

permitting removal of the front wall covers to provide access to the side openings for tube threading purposes without spilling the pellets, means for electrically connecting the boxes with a current source, and means for conducting a non-oxidizing gas under pressure into the boxes, said gas passing through the interstices between the pellets and through the side openings in the boxes and into the tubular sections.

2. Apparatus according to claim 1 in which the tubular sections are secured in position by pairs of clamping members, one member of each pair being fixed to the frame and the other member of each pair being supported by the fixed member of each pair, some of the pairs of clamping members directly contacting refractory lining bodies and comprising fixed members which are provided by the side walls of the boxes and removable members which are carried by the removable covers of the boxes.
